UNITED STATES PATENT OFFICE.

DAVID McINTYRE, OF DETROIT, MICHIGAN.

BUILDING BLOCK.

Application filed August 23, 1922. Serial No. 583,689.

To all whom it may concern:

Be it known that I, DAVID McINTYRE, a citizen of the United States, and residing at Detroit, in the county of Wayne and State 5 of Michigan, have invented a new and Improved Building Block, of which the following is a specification.

This invention relates to the construction of machine molded building blocks, and its 10 object is to provide a block of this character with suitable air spaces and partitions between them to brace the outer walls of the block, the outer walls and the ends of the partitions being widened at one surface of 15 the block to supply sufficient area to receive mortar. Another object of this invention is to provide a block of this character which can be readily subdivided without waste. A further object of this invention is to provide 20 a block of this character with a central transverse partition which facilitates the handling thereof, one end of this partition being widened so that the block can easily be carried.

25 In the accompanying drawing, Fig. 1 is a plan of my improved block. Fig. 2 is a section in the line 2—2 of Fig. 1. Fig. 3 is a plan of a modified form of block.

Similar reference characters refer to like 30 parts throughout the several views.

The block shown in Fig. 3 comprises end walls 1, side walls 2, main partition walls 3 and a central inner partition wall 4 connecting the middle portions of the main partition walls 3. The end and side walls are formed with inwardly extending flanges or 35 ledges 5 at what is the upper face of the block when in a building to afford space to receive mortar in which the lower edges of 40 these walls of another block may rest.

The upper end of the central partition 4 is also shown formed with flanges on ribs 6 to facilitate handling of the block, slipping being thereby prevented.

45 It often happens that a building block is too long, and as these blocks are usually made of concrete or terra cotta which have no line of cleavage, many blocks are broken into useless pieces in the attempt to shorten them. I have found that forming the main partition walls of two parallel thicknesses 7 with air spaces 8 between them, provides a block which can be shortened by striking the side walls of the block along this air space 55 with the edge of a masons trowel.

The air spaces 8 are preferably narrow so that the walls 2 will break along substantially straight lines. These air spaces are also preferably spaced about one-fourth the length of the block from the adjacent ends 60 so that sectional blocks one-fourth, one-half and three-fourths of the length of the original block can be readily obtained. Furthermore, because of these division spaces which permit breakage along straight lines, substantially no loss occurs.

The proportions of the partitions and their number and the sizes of the air spaces may all be changed by those skilled in the art without departing from the spirit of my 70 invention as set forth in the following claims.

I claim:—

1. A building block substantially rectangular in area comprising two outer walls 75 and two partition walls parallel to each other, two other outer walls connecting to the ends of the first four walls and adapted to be broken from the ends of the two partition walls to reduce the length of the block, 80 and an inner partition wall connecting the middle portions of the other partition walls said parallel partition walls being formed of two parallel parts separated by narrow air spaces, the outer walls of the block and the said inner partition wall having ledges 85 at their upper ends.

2. A building block substantially rectangular in area comprising two outer walls and two partition walls parallel to each 90 other, two other outer walls connecting to the ends of the first four walls, and an inner partition wall connecting the middle portions of the other partition walls, said parallel partition walls being formed of two 95 parallel parts separated by narrow air spaces.

3. A building block substantially rectangular in area comprising two outer walls and two partition walls parallel to each 100 other, two other outer walls connecting to the ends of the first four walls, and an inner partition wall connecting the middle portions of the other partition walls, said parallel partition walls being formed of two 105 parallel parts separated by narrow air spaces, the distance between said air spaces in the partition walls being substantially half the length of the block.

DAVID McINTYRE.
